ABSTRACT OF THE DISCLOSURE

In a process wherein an organic halide is reacted with an organic acid to obtain the corresponding ester, the improvement to increase the amount of ester which involves carrying out the reaction in the presence of water.

This application is a continuation-in-part application of our application Ser. No. 785,794, filed Dec. 20, 1968, entitled "Process For Producing Esters," now abandoned.

This invention relates to a process for preparing esters, particularly a process for reacting an organic halide with an organic acid to obtain the corresponding ester.

An organic halide can be made to react with an organic acid to obtain the corresponding ester and water, for example, as in Canadian Pat. No. 765,833 to William L. Walsh, but unfortunately, particularly to low temperatures, the reaction proceeds with difficulty and, many times, with undesirably small amounts of ester. We have found that the amount of ester produced in such reaction can be greatly increased by the mere expedient of carrying out the same in the presence of a relatively large amount of water.

The first reactant that is employed herein includes monobasic organic acids as defined in said Canadian Pat. No. 765,833, such as saturated straight chain aliphatic monobasic organic acids, that is, carboxylic acids, having from two to 30 carbon atoms, preferably from two to 22 carbon atoms; saturated branched chain aliphatic monobasic acids having from two to 30 carbon atoms, preferably from two to 22 carbon atoms, aromatic monobasic acids, saturated cyclic monobasic acids and straight and branched monobasic olefinic acids having from three to 22 carbon atoms, preferably from six to 22 carbon atoms. The first reactant can also include dibasic organic acids such as aliphatic straight and branched chain dibasic acids having from four to 22 carbon atoms, preferably from four to 18 carbon atoms, straight and branched chain olefinic dibasic acids having from four to 22 carbon atoms, preferably from four to 18 carbon atoms, cyclic dibasic acids having from five to 22 carbon atoms, preferably from five to 18 carbon atoms, and aromatic dibasic acids having from eight to 32 carbon atoms, preferably from eight to 18 carbon atoms; and polybasic acids

having from four to 22 carbon atoms, preferably from four to 18 carbon atoms.

To react with the monobasic and dibasic acids defined above to produce the desired ester in accordance with the process defined and claimed herein there must be employed an organic halide selected from the group consisting of primary straight and branched chain alkyl halides having from one to 30 carbon atoms, preferably from one to 22 carbon atoms; secondary straight and branched chain alkyl halides having from one to 30 carbon atoms, preferably from one to 22 carbon atoms; primary cyclic halides having from four to 22 carbon atoms, preferably from four to 12 carbon atoms; secondary cyclic halides having from three to 22 carbon atoms, preferably from three to 12 carbon atoms, primary straight and branched chain olefinic halides having from three to 22 carbon atoms, preferably from six to 22 carbon atoms; and secondary straight and branched chain olefinic halides having from three to 22 carbon atoms, preferably from six to 22 carbon atoms. Specific examples of each of the monobasic organic acids and organic halides that can be used herein are set forth in said Canadian Pat. No. 765,833, referred to above. Examples of dibasic acids that can be employed include specific examples of aliphatic straight and branched dibasic acids, such as succinic acid, glutaric acid, adipic acid, pimelic acid, azelic acid, sebatic acid, suberic acid, methylsuccinic acid, dimethylsuccinic acid, methyladipic acid, etc.; specific examples of straight and branched olefinic dibasic acids, such as maleic acid, fumaric acid, methylmaleic acid, dimethylmaleic acid, ethylmaleic acid, methylfumaric acid, dimethylfumaric acid, chloromaleic acid, dichloromaleic acid, glutaconic acid, etc.; specific examples of cyclic dibasic acids, such as cyclohexane dicarboxylic acid, cyclopentane dicarboxylic acid, cyclododecane dicarboxylic acid, etc.; specific examples of aromatic dibasic acids, such as ortho-phthalic acid, nitrophthalic acid, tetrachlorophthalic acid, etc., and specific examples of polybasic acids, such as tricarboxylic acid, aconitic acid, citric acid, etc. of the organic halides defined above, we prefer to employ alkyl halides, particularly primary alkyl halides. Of the alkyl halides, we prefer alkyl chlorides and alkyl bromides. Although we prefer to employ the organic acids and the organic halides in approximately stoichiometric amounts, the molar proportions thereof can vary from about 10:1 to about 1:10.

As noted, the amount of ester produced is considerably enhanced by carrying out the reaction in the presence of water. The molar ratio of water to the organic halide reactant defined above can be from about 1:1 to about 50:1, but preferably is about 2:1 to about 40:1.

In carrying out the reaction, the reactants defined above and the water are merely brought together in any convenient manner. The temperature can be as low as about 100° and as high as about 250° C., but preferably is about 55 120° to about 200° C. At the low temperatures, the reaction proceeds slowly, while at the higher temperatures shorter reaction times are required and the production of alcohols corresponding to the organic halide and some

olefins and a slight increase in ether are obtained. Pressures are not critical and any pressure is suitable, but in order to maintain water in the reaction zone, a pressure of at least about one hundred pounds per square inch gauge is preferred and pressures up to about 1000 pounds per square inch gauge can be used. The reaction time is similarly not critical and is dependent upon the other variables involved and on the amount of conversion desired. In general, a reaction time of about one minute to about 40 hours, preferably from about 15 minutes to about three hours can be used.

During the course of the reaction, an ester, hydrogen halide, water and some alcohol, ether and olefin are produced. The ester can be recovered from the reaction product in any convenient manner. For example, upon cooling, the reaction mixture resolves itself into an aqueous layer and an organic layer. Depending on the density of the organic product formed, the organic layer can be either the upper or lower layer. The two layers can be separated from each other in any convenient manner. For example, by decantation. The organic layer will contain the organic components and the same can be separated from each other in any suitable manner, for example, by distillation. The aqueous layer contains the water originally present, water that formed, unreacted organic acid and hydrogen halide. It is believed that the hydrogen halide complexes or in some manner attaches itself to the water. The complex exists as a liquid. The aqueous layer can be discarded, if desired, but in a preferred embodiment, the hydrogen halide and unreacted organic acid can be recovered by subjecting the aqueous layer to distillation at low pressures, for example, 100 millimeters of mercury, to remove substantially all of the uncomplexed water and organic acid overhead, after which the complex is subjected to distillation at an elevated pressure, for example, 75 pounds per square inch gauge, to remove substantially anhydrous hydrogen halide overhead.

The process defined herein can be further illustrated. The following procedure describes the first sixteen runs. Into an 1800 milliliter stirred tantalum autoclave there was introduced an organic halide, an organic acid and, in some runs, water. The contents of the autoclave were raised to reaction temperature and pressured to about 200 to about 300 pounds per square inch gauge. After holding the contents of the autoclave for a selected period of time under the above conditions, the autoclave was permitted to cool to room temperature, opened, and the contents were found to be present as two layers, an

aqueous layer and an organic layer. The latter was analyzed by gas liquid chromatography.

The following procedure describes Runs No. 17, 18 and 19. Into a 300 milliliter glass pressure reactor there was introduced an organic halide, a dibasic acid and water. The glass reactor was placed in a shielded cage and the contents stirred by a magnetic stirrer. The contents of the glass reactor were raised to reaction temperature and pressured 100 to 150 pounds per square inch gauge. After holding the contents of the glass reactor for a selected period of time under the above conditions, the glass reactor was permitted to cool to room temperature, opened, and the contents were found to be present as two layers, an aqueous layer and an organic layer. The latter was analyzed by gas liquid chromatography.

The data obtained using propionic, valeric and pelargonic acids as the organic acid components are set forth in Table I. Data from the runs using o-phthalic acid are set forth in Table II.

The uniqueness of the present process is apparent from a study of the data. In each instance wherein water was added to the reaction system, the amount of ester was greatly increased. As the temperature was increased, the amount of olefin and ether was slightly increased, but fortuitously, the amount of alcohol was also increased. Since the alcohol obtained corresponds to the organic halide employed, this is advantageous, since such alcohols are commercially desirable. In fact, it would be commercially attractive to convert the esters produced to the corresponding alcohols by hydrolysis. To the extent that alcohols are so produced, the commercial attractiveness of the present process is thereby enhanced.

The results obtained herein are completely unexpected. In the present process an organic halide is being reacted with an organic acid to obtain the corresponding ester of such reactants. One skilled in the art would not expect that the addition of water to such reaction system would produce beneficial results, that is, increase the amount of ester, but would expect, in fact, that if any reaction would take place, hydrolysis of organic halide would result.

Although the reaction of organic acids with organic halides to produce esters in the presence of water is the new procedure described and defined herein, it may be pointed out that instead of the organic acid, its anhydride can be charged to the reaction zone and the reaction proceeds to give the same product, since the anhydride, in the presence of water, is converted to the corresponding organic acid in situ. In an important commercial operation, phthalic anhydride would preferably be used rather

than phthalic acid because of its greater availability. We have, in fact, carried out the reaction with both phthalic acid and phthalic anhydride and obtained substantially similar results.

5 Obviously, many modifications and variations of the invention, as hereinabove set forth, can be made without departing from the spirit and scope thereof, and therefore only such limitations should be imposed as are indicated in the appended claims.

10 We claim:

1. A process for preparing an ester which comprises reacting an organic acid selected from the group consisting of monobasic organic acids and polybasic organic acids with an organic halide selected from the group consisting of a primary alkyl halide, a secondary alkyl halide, a primary cyclic halide, a secondary cyclic halide and an olefinic halide in the presence of a relatively large amount of water.

2. The process of claim 1 wherein the amount of water relative to said organic halide on a molar basis is from about 1:1 to about 80:1.

3. The process of claim 1 wherein the amount of water relative to said organic halide on a molar basis is from about 2:1 to about 40:1.

25 4. The process of claim 1 wherein the reaction temperature is about 100° to about 250° C.

5. The process of claim 1 wherein the reaction temperature is about 120° to about 200° C.

6. The process of claim 1 wherein the reaction time is about one minute to about 40 hours.

7. The process of claim 1 wherein the reaction time is about 15 minutes to about 3 hours.

8. The process of claim 1 wherein the organic acid is a monobasic organic acid.

35 9. The process of claim 1 wherein the organic acid is a dibasic organic acid.

10. The process of claim 1 wherein the organic halide is a primary alkyl halide.

40 11. The process of claim 1 wherein the organic halide is a primary alkyl bromide.

12. The process of claim 1 wherein the organic halide is a secondary alkyl bromide.

45 13. The process of claim 1 wherein the organic halide is a primary cyclic halide.

14. The process of claim 1 wherein the organic halide is a secondary cyclic halide.

15. The process of claim 1 wherein the organic acid is propionic acid.

50 16. The process of claim 1 wherein the organic acid is valeric acid.

17. The process of claim 1 wherein the organic acid is pelargonic acid.

55 18. The process of claim 1 wherein the organic acid is o-phthalic acid.

19. The process of claim 1 wherein the organic halide is 1-bromohexane.

60 20. The process of claim 1 wherein the organic halide is 1-bromoocctane.

21. The process of claim 1 wherein the organic halide is 1-bromodecane.
